UNITED STATES PATENT OFFICE.

CHRISTOPHER W. LEVALLEY, OF MILWAUKEE, WISCONSIN.

CONVEYER.

No. 832,986.

Specification of Letters Patent.

Patented Oct. 9, 1906.

Application filed February 20, 1906. Serial No. 302,027.

To all whom it may concern:

Be it known that I, CHRISTOPHER W. LEVALLEY, a citizen of the United States, residing at Milwaukee, in the county of Milwaukee and State of Wisconsin, have invented a new and useful Improvement in and Relating to Conveyers, of which the following is a specification.

My invention relates to endless carriers in which is employed a single line of belting, usually sprocket-chain belting, from which are suspended a series of swinging load-carriers, the latter being mounted upon axes disposed substantially parallel with the axes of articulation of the elements of the endless carrier and arranged entirely to one side of such carrier. An example of this type of conveyer is described and illustrated in my Patent No. 799,993, of September 19, 1905.

In the accompanying drawings, Figure 1 is an elevation of the upper part of a conveyer employing my invention. Fig. 2 is an edge view thereof. Fig. 3 is a front view of one of the hangers or frames of the swinging carrier. Fig. 4 is an edge view of the part shown in Fig. 3. Figs. 5 and 6 are detail views of the carrier-engaging attachments applied to the steadyng and guiding wheel.

In the accompanying drawings, 2 represents the endless element of the conveyer, which is represented as being formed of articulated sprocket-links arranged to engage with a head sprocket-wheel 3. These parts may be of any usual construction, and I have therefore deemed it unnecessary to show the lower supporting-wheel, around which the chain belt passes. The chain carries a series of package or article supports 4, mounted upon outwardly-projecting studs or pivot pins 5. These latter are arranged to extend outward from the side bars of certain of the links of the chain and are substantially parallel with the axes of the connecting-pins of the chain-links. This causes the carriers or supports for the loads transported by the conveyer to be disposed entirely to one side of the chain, so that it may travel the entire circuit of the conveyer and past the face of the head-wheel, where the direction of the conveyer is changed without having its relation to a horizontal plane disturbed.

In operating with this type of conveyers it sometimes happens that vibration will be imparted to the suspended load-carriers as they pass the head-wheel, and I have therefore devised a steadyng-support and guide

for maintaining them in proper position during the time the change from the up to the down run of the conveyer is being made—that is, while the supports or carriers are being moved around and across the face of the wheel 3.

6 represents a sprocket-wheel of the same size as the wheel 3. It is situated between the two lines of the endless belt and directly below the head-wheel 3 and is mounted upon a shaft or stud 7. It is formed with sprocket-teeth 8, that are adapted to be engaged by the chain, the up-moving line of chain engaging with the wheel on one side and the down-moving line with it upon the opposite side. The wheel 6 is thus positively driven by the chain and its movements synchronized with those of the wheel 3, which has also sprocket engagement with the chain.

Each support or carrier 4 is provided with an arm 9, that is arranged to engage with some part of the guiding-wheel 6 during the time the carrier or load-support is making the turn about the head-wheel 3. I prefer that this arm 9 should depend centrally from the lower cross-bar 10 of the frame of the carrier or load-support and that its end should be somewhat offset and provided with a pin 11. This pin is adapted to engage with one of the forked attachments 13, detailed in Figs. 5 and 6, applied to the guiding and steadyng wheel 6.

14 designates a guide alongside the conveyer just below the head-wheel and in position to engage with the side of the hanger or carrier 4, which may be formed with a wearing-surface 16 for such engagement, if this be found desirable. The upper end of the guide extends inward toward the line of the chain or belt 2, as indicated at 15, forming a sort of cam that operates to shift the passing carrier or load-support laterally to a slight extent in order to cause a good engagement of the arm 9 with one of the forks 13, carried by the wheel 6.

As the wheels 3 and 6 travel with exactly the same speed, it follows that if the support or carrier for the load has engagement with each of them at corresponding points the carrier must be maintained in fixed relation to horizontal planes so long as such engagement is maintained, and all possibility of the swinging of the carrier is eliminated. Such conditions are insured by the construction I have illustrated and described. To insure the proper register and engagement of the

projections carried by the load-support, such as the arms 9, and the projections or parts of the wheel that engage therewith, such as the forks 13, the wheel 6 should be positively driven at the same speed as the wheel 3, and this I secure without any intervention of gearing, the presence of which is always objectionable when it can be dispensed with, by providing the wheel with teeth, sprockets, or other devices adapting it to be directly and positively driven by the chain or belt 2.

It will be understood that the use of the guide 14 15 is not essential to my invention, as the parts 9 and 13 will ordinarily properly come together without means for positively forcing them into engagement; but I prefer to use the guide, as it insures against any accident or misregister of these parts.

20 What I claim is—

1. In a conveyer, the combination of an endless belt, supports for loads suspended therefrom, a head-wheel around which the endless belt passes, and a rotating guide for the load-supports arranged below the head-wheel, between the opposite lines of the belt, and arranged to be directly and positively driven by the belt, substantially as set forth.

2. In a conveyer, the combination of a head-wheel, an endless belt arranged to pass around such wheel, swinging carriers or supports for the loads conveyed arranged entirely to one side of the endless belt and connected thereto, and a guide and steadyng

device for the load-carriers as they pass the 35 turning - wheel arranged below the head-wheel, such guide being movable across the conveyer from the uprun of the endless belt to the downrun thereof on a path substantially parallel with that followed by the belt 40 as it makes the turn about the head-wheel, and the guide being driven directly by the endless belt, substantially as set forth

3. In a conveyer, the combination of a head-wheel, an endless belt, load - carriers 45 suspended from the belt and arranged entirely to one side thereof, a guiding device with which the load-carriers are adapted to engage arranged adjacent to the head-wheel, and means for forcing the load-carriers into 50 positive engagement with the said guiding device, substantially as set forth.

4. In a conveyer, the combination of a head-wheel, an endless belt passing around the same, the carriers 4 suspended from the 55 chain and each provided with an arm 9, a spocket-wheel 6 situated below the head-wheel and between the up and down moving lines of the endless belt and arranged to engage therewith and be directly driven thereby, and the attachments 13 carried by the wheel 6 and arranged to engage with the arms 9 of the load-carriers as they pass the head-wheel, substantially as set forth.

CHRISTOPHER W. LEVALLEY.
